(57) **CLAIM**

The ornamental design for a applicator device, as shown and described.

DESCRIPTION

FIG. 1 is a front view of a applicator device of the present invention.

FIG. 2 is a rear view of the applicator device of FIG. 1.

FIG. 3 is a top plan view of the applicator device of FIG. 1.

FIG. 4 is a bottom view of the applicator device of FIG. 1.

FIG. 5 is a right side view of the applicator device of FIG. 1.

FIG. 6 is a left side view of the applicator device of FIG. 1.

FIG. 7 is a perspective view from below of the applicator device of FIG. 1.

FIG. 8 is a front view of the applicator device of FIG. 1 in use, wherein the cap part of the device is pressed down, allowing, for example, a transmission plate in the device to push down on a microneedle array on a subject's skin, allowing needles in the array to penetrate the skin; and,

FIG. 9 is a perspective view from below of the application device of FIG. 1, from the opposite side shown in FIG. 7.
